CARTON FOLDER

Edward J. Pagendarm, San Mateo, Calif., assignor
to Bemiss-Jason Company, a corporation of
California.

Application April 7, 1947, Serial No. 739,749

9 Claims. (Cl. 93—51)

1

This invention relates to the making of cartons, boxes, trays or other structures formed from blanks of cardboard, paperboard and other foldable material.

The invention provides a method of forming boxes, cartons, or trays hereinafter collectively referred to briefly as "boxes" or "folding boxes" from flat blanks of foldable sheet material, the method, by reason of its peculiar characteristics, being particularly adaptable to performance by automatic machinery.

This invention also provides an improved device for carrying out the novel method.

The invention is primarily concerned with the setting up of boxes from blanks having a bottom, side panels and end panels hingedly connected to the bottom, and having flaps hinged to certain of said panels, the flaps being insertable into cuts in other panels to lock the box together.

The invention is particularly adapted to the making of boxes which are maintained in set up condition by a glueless interlock of cut edges formed on or in the box elements to be interlocked, as will be described hereinafter by way of a typical example. However, the invention is not limited to such boxes nor to any particular form of interlock employing cut edges, but may also advantageously be employed for the setting up of boxes employing other forms of glueless interlocks.

In order that the invention may be better understood, it will now be described with reference to the accompanying drawings in which:

Figure 1 is a plan of the die and plunger with certain parts in section;

Figure 2 is a section along the line 2—2 in Figure 1;

Figure 3 is a section along the line 3—3 in Figure 2;

Figure 4 is a plan view of a typical box blank adapted to be handled in the illustrated folding die;

Figure 5 is a view showing an initial stage in the assembly of the blank of Figure 4;

Figure 6 is a plan view of the completed box made from the blank shown in Figure 4;

Figure 7 is a side view of the box shown in Figure 6;

Figure 8 is an outside view of a corner portion of a folding box of modified construction embodying the invention, the box panels being shown in semi-assembled position prior to the performance of a final step in locking the panels together;

2

Figure 9 is an inside view, partly in section, of the corner portion shown in Figure 8;

Figure 10 is an outside view of the corner portion shown in Figure 8 after performance of a final step in locking the panels together;

Figure 11 is an inside view, partly in section, of the corner portion shown in Figure 10;

Figure 12 is a plan view of a die and plunger mechanism, somewhat similar to that shown in Figure 3, the mechanism being particularly adapted to assembly of a container embodying the construction shown in Figures 8 through 11;

Figure 13 is a section taken along the line 13—13 of Figure 12;

Figure 14 is a plan view of a modified form of button cam utilized to effect an interlock of the modified form of corner shown in Figures 8 through 11;

Figure 15 is a fragmentary plan view of still another form of container blank having a first and a second panel, the two being interlocked upon insertion of portions of the first panel into suitable apertures provided in the second panel, the two panels being in a face-to-face engagement;

Figures 16 and 17 are side elevations of the interior of a container corner illustrating the assembly of the structure shown in Figure 15;

Figure 18 is an end view of a die and plunger of modified type, certain portions being in section;

Figure 19 is a side view of the plunger shown in Figure 18;

Figure 20 is a plan view of the die and plunger of Figures 18 and 19, parts being in section;

Figure 21 is a plan view of the face of the plunger; and

Figure 22 is a fragmentary view of the die, partly in elevation and partly in section.

The die structure shown in Figures 1—3 will be first described in detail and then its operation will be described on the blank shown in Figures 4—7. As appears particularly in Figures 1 and 2, the die structure includes a first side member 171 and a second side member 172 slidably mounted in a suitable frame 173 of a box machine, the two members providing a receiving station for a cut and scored blank. The two die members are slidably drawn toward each other by springs 174, the distance between them being regulated by stops 176.

In Figures 4 to 7, inclusive, a form of blank 151 is shown which may be assembled by the plunger and die of the specific form shown in Figures 1, 2 and 3. The blank has a bottom 152

and end walls 153 from which wings 154 extend. The end walls are foldable about fold lines 156 while the wings are foldable about fold lines 157. Side walls 158 are also connected to the bottom and are foldable with respect to the bottom about fold lines 159. Each of the side walls 158 and wings 154 interlock by means of an arcuate internal cut 161 formed therein and extending generally transversely of the side wall to form a tongue 162 projecting toward the adjacent wing 154. The side walls may also be cut away or notches as at 163 adjacent each wing to facilitate alignment for assembly, though this is not essential. The wing is cut to provide an edge 164 in such a position that it can be engaged with at least a portion of arcuate internal cut 161. Edge 164 and the portion of internal cut 161 which it engages are shown at 90° to one another and are spaced the same radial distance from the common corner about which they are hingedly mounted. Of course, the 90° relationship obtains only in a container wherein this is the final angular relationship between the end and the bottom and the wing and the bottom. If this final angular relationship is to be otherwise, for example, 130°, then the angle between face 164 and the cooperating portion of the cut 161 should be modified accordingly.

The die structure shown in Figures 1-3 includes means for flexing each tongue 162 with respect to the panel in which it is formed to receive a wing in the opened cut and interengage edge 164 on the wing with an edge portion on cut 161. To this end, each die member is provided with four sloping curved surfaces or slides 181, 182, 183 and 184 over which the blank is moved. Beyond slides 181 and 184, each die member is additionally arcuately formed at 186 and 187, the arcuate surfaces being continued by downwardly projecting members 188. On each of the members 188 spring members 189 are mounted, the latter extending inwardly to provide resilient folding surfaces in the die. The spring members 189 are supported by adjustable studs 191 projecting through and secured to each of members 188. The spring mounting of the die members and the use of spring fingers 189 protect the die against damage if accidentally several blanks are simultaneously forced through the die by the positively moved plunger.

Pins 171 are provided on the die member 172 for aligning blanks fed into the die with respect to the plunger, the pins fitting into the cutaway portion 163 adjacent each wing. Each pin is adjustably carried on an arm 178 which can be locked, each pin projecting through an arcuate aperture 179 in die member 172.

The plunger 42 fits the previously described die structure to force a flat blank therethrough in such a manner that the blank is assembled to a desired extent. In the illustrated form of device, the end surface of the plunger corresponds in general outline to the bottom 152 of the blank 151. In order to make this readily apparent, the blank of Figure 4 is indicated in dotted outline in Figure 1 in the position which it regularly assumes with respect to the die and the plunger. The sides of the plunger are relieved as at 192 except in the intermediate portions 193 which cooperate with the projecting slides 182 and 183 as will be presently described. Also, mounted upon the flared portions 193 on the plunger are buttons 194 for flexing the tongues and side walls with respect to one another.

The construction of the die and plunger of

Figures 1-3 and the functioning of the various elements will become further apparent upon the following description of their operation: If a blank corresponding in outline to that shown in Figure 4 is fed into the device, the pin stops 171 engage notches 163 in the blank and accurately align the blank with respect to the end surface of the plunger. Upon advancement of the plunger toward the die, either by hand or by power, the blank is forced against the die and engages slides 181, 182, 183 and 184 which fold the sides 158 of the blank upwardly about fold lines 159 until the side panels are substantially normal to the bottom 152 (Figure 5).

Continued movement of the plunger with respect to the die moves the end walls 153 and wings 154 over the arcuate surfaces 186 and 187 until end walls 153 are raised and the wings project upwardly, as appears in Figure 5. By this time the blank has passed partially through the die and the side walls of the blank are retained between slides 182 and 183 on the die members and the flared portions 193 on the plunger. The relation of these surfaces is such that, together with the buttons 194, each tongue 162 is flexed with respect to its supporting panels so that the wings 153 can be threaded between the upstanding side walls 158 and the projecting tongue 162 upon further folding of the end walls 153. The buttons 194 provide projecting surfaces which, with the cooperatively placed slides 182 and 183, apply pressure on each side wall and flex the side wall and tongue relative to each other so that the one is displaced from the plane of the other. In the illustrated form of plunger and die the tongue is moved out of the plane of the side wall panel. However, the end of each side wall panel can be flexed inwardly and the tongues held stationary so that the wing passes over the flexed end of the side wall and passes through the arcuate cut and under the tongue.

When the end walls 153 are engaged by the spring fingers 189, the wings 154 are nearly parallel to the side walls 158 and move over the curved or arcuate surfaces 186 until they lie face to face with the upstanding side walls 158. During the continued movement of the plunger, the tongues permit the edge 164 to engage a portion of the cut 161. When this occurs, the wings 154 and the side walls 158 lie face to face and are under the pressure applied by the two die members against the plunger. To relieve this pressure partially, relief surfaces 199 are provided on the lower portion of the slides 181 and 184.

Continued movement of the plunger relative to the die moves the blank beyond the die members so that the blank is freed from the engaging surfaces of the die. In this condition, the edge 164 on each wing is in engagement with an edge provided by the arcuate cut 161 and is retained in this position by the tension exerted on the wing by the flexed tongue.

When the plunger is moved upwardly, the completed box structure is engaged by the ends of the slide members and is stripped off the plunger to fall upon a suitable movable conveyor.

If blanks are made of stock having relatively little resiliency, such as chipboard, it is sometimes desirable to provide a lock of the type shown in Figures 8 to 11 in which a tab or tip 160 forming the end of the cut edge 164 on the wing 154 extends beyond the confines of the cut 161, 165 which forms the tongue 162. When the tip 160 is forced from the initial position outside the side wall panel 158 as shown in Figures

8 and 9 through the cut 165 to the inside of the side wall panel 158 as shown in Figures 10 and 11, the two panels 158 and 154 are securely locked by engagement of edge 164 with edge 161, the tip portion 160 threaded or "buttoned" through the cut 165 preventing disengagement of the interlocking edges.

The form of blank shown in Figures 8 to 11 can be assembled by a die and plunger similar to the one shown in Figures 1 to 3. Referring to Figures 12 and 13, slides 182 and 183 are each provided with extensions 421 and 422, each of the extensions having button-like cams or projections 423 thereon. The movement of the blank past the cam-like buttons 423 suffices to place sufficient pressure upon the blank to move portions of the blank such as tab 160 through the cut in panel 158.

In Figure 14 a modified plunger construction is shown particularly useful for handling board having relatively little resiliency. In the illustrated plunger each button cam 194 has a projection 196 which, as the blank is pushed by it, positively deflects with its outer surface the tongue 162 with respect to its supporting panel. The under surface of the projection acts as a guiding surface over which the wing portion carrying the edge 164 moves into final position for locking. This construction may be used in assembling the form of blank shown in Figures 8 to 11.

The blank structure shown in Figure 15 is in some respects similar to that shown in Figures 8 to 11. The first panel 402 has a cut edge 431 thereon in such relation to the internal cut 407 in the second panel 403 that a portion 430 of the cut edge 431, upon interengagement of the cut edge 431 and cut edge 407, is adapted to be forced past the cut 407. In the completed interlock, the portion 430 projects beyond the cut 407, as shown in Figure 17. Figure 16 shows the panels in a face-to-face engagement prior to the forcing of the tip portion 403 through the cut 407. The force required for the operation can be applied by a button cam 423 or with a movable tongue-shaped element or wing hook as hereinafter described.

Instead of locking a wing element provided upon an end wall to a side wall, the interlock can be provided between an end wall and wings which extend from a side wall. This involves a mere reversal in parts and an obvious change in the arrangement of the elements involved.

In Figures 18 to 22 a further modification of the plunger and die is indicated, the modification of the plunger being specifically directed toward the end of assembling a blank wherein the tongue has a positive lock, for instance, that shown in Figures 8 to 11, and in Figures 15 to 17.

In this modified die and plunger construction, identical reference characters are used where the elements are identical with those previously disclosed. Thus the die comprises members 171 and 172 held together toward each other by springs 174 in a frame 173. They are suitably spaced by stops 176.

Referring particularly to Figure 20, there will be found slides or projecting surfaces 201, one at each corner of the box to be assembled. Center slides or surfaces 202 are provided, one on each die member. Outside the outlines of the box to be formed are support members 204. Corner slides or projections 203 are arcuately formed at 203 and support members 204 are arcuately formed at 205. This structure so far is only slightly modified from that heretofore described.

Pivottally mounted on support members 204 are other slides in the form of spring pressed folding members 206 which perform the same function as do elements 189, for example, in Figure 13. It will be noted that the folding members 206 like the members 189 in the device shown in Figure 13 extend beyond the width of the plunger to engage the folded edges of the wings 154 or 402 of the blank so that force is exerted on the wings directly, in the plane of the wings, to insert the wings into the corresponding cuts 161 or 407 of the blank. Adjustable locating pins 207 are mounted upon die members 172.

At each side of the die flat blank guiding springs 208 are secured to frame 173. Thumb-screws 209 are provided for making adjustments in the position of the guide springs.

The plunger 42 consists of a hollow box-like member having side walls 301 and end walls 302, 20 the bottom edges of which correspond to the flat face of plunger members heretofore described. The plunger is hollow to allow the introduction of means for exerting a positive force upon the wing members of the box blanks in order to interlock the wing member with the sides of the box.

To this end there are formed four integral plunger extensions 303 having at the outer ends slots 304. In each pair of slots 304 there is mounted a bar 305, making two bars for each 30 plunger. Each bar 305 may be positioned where desired in the slot 304 by means of nut 306. Four levers 307 are mounted, two on each cross bar and at each corner of the plunger. Intermediate the ends of these levers are rollers 309 and at the end 35 opposite the pivotal mounting are wing hooks 310. The relation among all these elements will be better understood by reference to Figure 18 wherein springs 311 are shown which press the inner ends of levers 307 towards their outermost position, determined by engagement with the side walls 301. In this position the wing hooks 310 project through openings 312 in the walls.

It should now be apparent that for each corner of the blank box to be assembled, there is a wing hook 310 protruding slightly from the sides of the plunger head 42. Each lever 307 is pivoted at its end and controlled by cooperation of the rollers 309 with the center slides 202 of the die, as shown, or with similar members, as may be desired.

The particular usefulness of the head thus disclosed is in connection with a box blank, such as that indicated in Figure 8, wherein there is provided a positive locking of the wing with the side wall of the box. To this end and as almost the last operation of the plunger, the levers 307 pull each of the four wings to the inside of the box when the rollers 309 strike the surfaces 202, thereby moving the ends of the levers 307 with their hooks 310 towards the interior of the plunger. This timing is assured by proper mounting of the rollers 309 with relation to the surfaces 202.

The adjustable mounting of the cross bars 305 in slots 304 is provided for the control of the inward movement of wing hooks 310, since too much movement might break off the wings, or at least weaken them unduly. The normal position of wing hooks 310 is such as to cause outward flexing of the tongues of the box side walls. As the end walls are folded into their proper position the wings slide under the hooks, and thereafter are pulled to the inside of the box.

It will be apparent that mechanically equivalent

means may be substituted for those which I have utilized, within the scope of this invention.

What is claimed is:

1. A device for converting into box form cut and scored box blanks of the type comprising a main panel, side panels, and end panels hingedly connected to the main panel, the device comprising oppositely disposed, spaced rigid side panel folding members mounted with freedom of movement towards, and away from, each other; means for biasing said folding members towards each other; pairs of oppositely disposed end panel folding members biased towards each other, said end panel folding members being mounted on, and movable with, said side panel folding members and defining a substantially rectangular die aperture therewith; and a reciprocable plunger movable through said die aperture.

2. A device for converting into box form cut and scored box blanks of the type comprising a main panel, side panels, and end panels hingedly connected to the main panel, the device comprising a die consisting of oppositely disposed side panel folding members having freedom to move towards and away from each other and means for biasing said side panel folding members towards each other, and oppositely disposed end panel folding members arranged transversely with respect to the side panel folding members and defining a substantially rectangular die aperture with the side panel folding members through which aperture a reciprocable plunger is movable, characterized in that said end panel folding members are mounted on, and movable with said side panel folding members, and that said end panel folding members are yieldable in a direction away from the path of the plunger.

3. A device for converting flat cut and scored box blanks into hollow box form comprising a reciprocable plunger, and a die through which said plunger is movable, said plunger including a projectable and retractable blank engaging element in its side, said die having a recess opposite said element to permit the plunger to pass through the die, with the blank engaging element in projected position, and means associated with said plunger and said die for moving said element in dependence on the position of the plunger relatively to the die as the plunger moves through the die.

4. A device for converting a cut and scored flat box blank into hollow box form, said blank having a main panel, a first box panel connected to the main panel along a first score line, said first panel having a cut therein adapted to be opened upon flexing of said panel on either side of the cut, a second box panel connected to the main panel along a second score line extending at an angle to said first score line, a lock flap hingedly connected to said second panel, said flap having a cut edge thereon formed to engage at least a portion of said cut in edge-to-edge engagement, said lock flap being foldable into a position in which it lies face to face with said first panel, said device comprising a die and a plunger movable through said die, said plunger having a base surface for engaging said main panel, said die having members for engaging and folding said first and second panels about said plunger and for moving said lock flap into face-to-face position with respect to said first panel, said plunger having a projectable and retractable hook shaped element in its side for engaging with its outer surface said first panel adjacent said cut to open said cut, said element being so located as to engage said lock flap with its inner surface and to pull said

lock flap toward the inside of the box, and means for positively retracting said element in dependence on the movement of the plunger through the die.

5. A device for converting a cut and scored flat box blank into hollow box form, said blank having a main panel, a first box panel connected to the main panel along a first score line, said first panel having a cut therein adapted to be opened upon flexing of said panel on either side of the cut, a second box panel connected to the main panel along a second score line extending at an angle to said first score line, a lock flap hingedly connected to said second panel, said flap having a cut edge thereon formed to engage at least a portion of said cut in edge-to-edge engagement, said lock flap being foldable into a position in which it lies face to face with said first panel, said device comprising a die and a plunger movable through said die, said plunger having a base surface for engaging said main panel, said die having members for engaging and folding said first and second panels about said plunger and for moving said lock flap into face-to-face position with respect to said first panel, said plunger having a projectable and retractable element in its side, said element being substantially hook-shaped and adapted to engage with its outer surface said first panel adjacent said cut to open said cut and permit passage of a portion of the lock flap therethrough into a position underneath the inner surface of the projection to enable the lock flap portion to be pulled to the inside of the box upon retraction of the element, and means for moving said element towards its retracted position in dependence on the relative position of the plunger relatively to the die, the die having a recessed portion opposite said hook-shaped element to permit the plunger to enter the die with the said element in projected position.

6. A device for converting a cut and scored flat box blank into hollow box form, said blank having a main panel, a first box panel connected to the main panel along a first score line, said first panel having a cut therein adapted to be opened upon flexing of said panel on either side of the cut, a second box panel connected to the main panel along the second score line extending at an angle to said first score line, a lock flap hingedly connected to said second panel, said flap having a cut edge thereon formed to engage at least a portion of said cut in edge-to-edge engagement, said lock flap being foldable into a position in which it lies face to face with said first panel, said device comprising a die and a plunger movable through said die, said plunger having a base surface for engaging said main panel, said die having members for engaging and folding said first and second panels about said plunger and for moving said lock flap into face-to-face position with respect to said first panel, said plunger having a projectable and retractable element in its side, said element being substantially hook-shaped and adapted to engage with its outer surface said first panel adjacent said cut to open said cut and permit passage of a portion of the lock flap therethrough into a position underneath the inner surface of the projection to enable the lock flap portion to be pulled to the inside of the box upon retraction of the element, a spring for biasing said element towards its projected position, and a lever deflectable by passage of the plunger through said die for retracting said element.

7. A device for converting a cut and scored flat box blank into hollow box form, said blank having a main panel, a first box panel connected to the main panel along a first score line, said first panel having a cut therein adapted to be opened upon flexing of said panel on either side of the cut, a second box panel connected to the main panel along a second score line extending at an angle to said first score line, a lock flap hingedly connected to said second panel, said flap having a cut edge thereon formed to engage at least a portion of said cut in edge-to-edge engagement, said lock flap being foldable into a position in which it lies face to face with said first panel, said device comprising a die member and a plunger member movable through said die member, said plunger member having a base surface for engaging said main panel, said die member having folding elements for folding said first and second panels about said plunger when the plunger member forces the blank past said folding elements, one of said members having a projectable and retractable element movable towards and away from said other member, said other member having a recess to permit movement of said projectable element in projected position past said other member, said projectable element being so located as to engage a blank portion and flex it into said recess, and means for projecting and retracting said element in dependence on the relative position of said plunger member relatively to the die member in its passage through said die member.

8. A device for converting a cut and scored flat box blank into hollow box form, said blank having a main panel, a first box panel connected to the main panel along a first score line, said first panel having a cut therein adapted to be opened upon flexing of said panel on either side of the cut, a second box panel connected to the main panel along a second score line extending at an angle to said first score line, a lock flap hingedly connected to said second panel, said flap having a cut edge thereon formed to engage at least a portion of said cut in edge-to-edge engagement, said lock flap being foldable into a position in which it lies face to face with said first panel, said device comprising a die member and a plunger member movable through said die member, said plunger member having a base surface for engaging said main panel, said die member having folding elements for folding said first and second panels about said plunger when the plunger member forces the blank past said folding elements, one of said members having a pro-

jectable and retractable element movable towards and away from said other member, said other member having a recess to permit movement of said projectable element in projected position past said other member, said projectable element being substantially hook-shaped and adapted to flex with its outside surface a blank portion into said recess in projected position, and to engage with its inside surface still another blank portion to flex said other blank portion in the opposite direction by retracting movement of said element, and means for projecting and retracting said element in dependence on the relative position of said plunger member relatively to the die member in its passage through said die member.

9. A device for converting flat cut and scored box blanks into hollow box form comprising a reciprocable plunger; and a die through which said plunger is movable, said plunger including a projectable and retractable blank engaging element in its side, said die having a recessed portion opposite said element into which a blank portion may be flexed by said element in projected position as the plunger passes through the die, said recessed portion extending longitudinally with respect to the path of the plunger to provide clearance for passage of said element through said die in projected position; means biasing said element towards its projected position; and means operable by the passage of the plunger through the die for retracting said element after said plunger and said element have entered said die.

35 EDWARD J. PAGENDARM.
